UNITED STATES PATENT OFFICE.

WILLIAM B. FENN, OF WINFIELD, NEW YORK, ASSIGNOR TO EZRA D. BECKWITH, OF LITTLE FALLS, NEW YORK.

WATER-BOTTLE.

SPECIFICATION forming part of Letters Patent No. 664,472, dated December 25, 1900.

Application filed February 7, 1900. Serial No. 4,335. (No model.)

To all whom it may concern:

Be it known that I, WILLIAM B. FENN, a citizen of the United States, residing at West Winfield, in the county of Herkimer and State 5 of New York, have invented certain new and useful Improvements in Water-Bottles, of which the following is a specification.

The present invention is in the nature of some specific improvements in the line of the 10 invention shown and claimed in my Patent No. 579,867, dated March 30, 1897.

The improvements consist, essentially, in a new and useful coupling device between the neck and the bottle proper and also in a novel 15 ice-receptacle to be used in connection with the bottle. These and other novel features will be hereinafter fully described and finally embraced in the clauses of the claim.

Referring to the accompanying drawings, 20 Figure 1 is a sectional view of the invention. Fig. 2 is a horizontal cross-section through line α α , Fig. 1.

Similar characters refer to similar parts throughout both views.

25 A represents the body portion of the bottle and which is provided with a large central opening A' and an annular rim B, surrounding said opening. The inner side or surface of this rim is made inclined in an inward direction for the purpose hereinafter mentioned.

C represents the neck of the bottle and which is detachably connected therewith and provided at its lower end with an inwardly-directed flange C', adapted to fit inside the rim of the bottle. Interposed between this flange and the said rim is a round rubber ring D. Connecting the neck with the bottle proper is a coupling composed of a band E, 40 having at its upper end an inwardly-tapering flange E', which engages the lower outer portion of the neck. Mounted inside this band is an expandable ring F, having three peripheral spirally-inclined surfaces F', which engage the inner sides of the band above mentioned. This ring is further provided with three outwardly-projecting studs F², which project through three slots E², cut through the sides of the band.

45 G represents an outer ring mounted on the

outside of the band and provided with three vertical slots G', adapted to engage the studs on the expandable ring. The lower edge of this ring is bent under the lower edge of the band in order to remain a permanent fixture 55 thereon.

H represents an ice-receptacle comprising a glass jar the upper end of which is provided with an outwardly-flaring rim H'. The outer surface of this rim is corrugated in order to permit the free flow of water in the bottle when the jar is suspended therein.

I represents the cover for the ice-receptacle and which is provided with an inclined edge I', adapted to fit inside the rim of the jar. Interposed between the edge of the cover and the rim of the jar is a round packing-ring J, adapted to provide a tight joint for the jar.

The ice-receptacle is mounted in the bottle by having the outer corrugated edge of the jar rest on the inclined inner surface of the rim of the bottle proper. A pressure is exerted on the cover of the jar by means of a spring K, removably mounted in the neck of the bottle. This spring is preferably made 75 of sheet metal and is composed of a plate or disk having three upwardly-extending arms K', the end portions of which are curved in order to conveniently snap into the groove formed by the flange C' in the lower end portion of the neck. The cover of the jar is preferably provided with a knob 13 for facilitating the handling of the cover. The jar may be substituted by a receptacle for filter material. The jar should then be open at its 80 bottom and the rubber ring placed between the outer side of its rim and the rim of the bottle proper.

In attaching the neck to the bottle proper the outer ring is rotated and transmits its 90 motion to the inner expandable ring by means of the projecting studs. The band is held stationary by the other hand. The spirally-curved surfaces of the expandable ring engage the inner sides of the band and cause 95 the expandable ring to contract and engage the annular bead or lip situated on the outer side of the rim of the bottle proper. By reversing the motion of the outer ring the expandable ring is made to expand, and thus re- 100

leases its engagement with the lip on the rim of the bottle and enables the neck to be removed from the bottle.

I do not desire to limit myself to the particular construction herein shown and described, as I am aware that various changes may be made therein without departing from the spirit and scope of my invention, but hold myself at liberty to make such changes as the state of the art will permit.

Having thus described my invention, what I claim as new, and desire to secure by Letters Patent, is—

1. In a water-bottle, the combination with the body A, the detachable neck C, the coupling-band E, the expansible ring F having peripheral spirally-inclined surfaces and studs F² projecting through said band, the ring G mounted on the outer side of the band and

engaging the said studs, substantially as described.

2. In a water-bottle, the combination with the bottle and its detachable neck, a coupling-band having an expansible ring mounted on its inner side, said ring being capable of contracting and engaging projections on the bottle proper, means for rotating the expansible ring, substantially as described.

3. In a water-bottle composed of separable sections and having a contracted neck, an ice-receptacle removably mounted in said bottle so as to leave passages for the water between its upper portion and the inner sides of the bottle, substantially as described.

WILLIAM B. FENN.
